MASSAGE CHAIR

William N. Moxley, Los Angeles, Calif.

Application July 21, 1955, Serial No. 523,523

11 Claims. (Cl. 128—33)

The present invention relates to apparatus for imparting a massaging action to the human body, and more particularly to chairs capable of imparting a massaging action to persons seated thereon.

An object of the invention is to provide a chair embodying a massage or vibration producing unit, in which the massaging action is conveyed effectively from the unit to all parts of the chair. The massage unit is mounted on the chair in such position that the massaging action is transmitted substantially uniformly throughout the chair.

Another object of the invention is to provide a chair embodying a massage or vibration producing unit, in which the massaging action of the unit is transmitted, with a high degree of effectiveness, to the lower regions of the back of the person seated in the chair, as well as to other desirable regions of the person's back and body.

A further object of the invention is to provide a chair containing an improved supporting structure for securing the massage unit to the chair, in order that a massaging action will be imparted to various regions of the chair and to the body of the person seated thereon.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a side elevational and vertical sectional view through a chair embodying the invention;

Fig. 2 is a bottom plan view of the chair disclosed in Fig. 1;

Fig. 3 is an enlarged sectional and elevational view taken generally along the line 3—3 on Fig. 1.

As disclosed in the drawings, the invention is incorporated in a chair having a seat 10 and a back portion 11, as well as spaced arm rests or arm portions 12 at the chair sides. The chair includes a frame that may be made of wood or similar rigid material, this frame including a front portion 13, a rear portion 14, 14a, and intervening side portions 15 appropriately secured to the rear and front portions 14, 13. Feet 16, adapted to rest upon the floor, may be secured at the bottom of the frame at the four corners of the chair.

The back 11 of the chair may extend upwardly from the rear 14, 14a of the frame, or from the portion 14a of the chair that may be disposed forwardly of the rear end 14 of the frame. As disclosed in the drawings, the rear of the frame may include the vertical portion 14 from which the forward horizontal portion 14a extends. The specific structure of the frame rear, however, may be changed, depending upon the character of the chair. As an example, the back 11 of the chair may be fixed with respect to the frame, or it may be adjustably mounted

2

with respect thereto, in order to allow the back to be disposed in the upright position disclosed, or to be tilted backward to a partial or fully reclining position. Similarly, the front 13 of the frame, or at least a part thereof, 5 may be fixed or may be adjustably mounted so as to swing upwardly to provide a support for the legs of the person seated in the chair.

The back 11 of the chair, as well as the seat 10, front portion 17 and arm portions 12 are padded, preferably 10 through the use of foam rubber, that bears against the frame structure. A suitable covering material 18 is disposed over the foam rubber, as is usual in upholstered or padded chairs.

It is desired to impart a massaging action to regions 15 of the body of a person seated in the chair, the massaging or vibrating action being transmitted through the frame of the chair, and through the rubber or rubber-like padding material, to the person's body. The unit 19 for imparting the massaging or vibratory action to the person's body is secured to the bottom portion of the frame. It is carried on a steel sub-frame 20 secured to the side and rear portions 15, 14a of the chair frame.

The sub-frame 20 specifically disclosed in the drawings is of angle iron construction. It includes a rear angle iron member 21 attached to the rear frame portion 14a, as by 25 means of vertically disposed screws 22 extending upwardly through the horizontal flange 23 of the rear member 21 into the rear portion of the frame, and also by horizontal screws 24 extending through the vertical flange 25 and threaded into the wooden frame 14a. As is evident from 30 the drawings, the horizontal flange 23 engages the undersurface of the wood frame member 14a, whereas the vertical flange engages the front of the rear wood frame member 14a. A vertical intermediate frame member 26 35 may be disposed immediately above the angle iron frame 21, extending upwardly to the padded seat portion 10 of the chair.

The sub-frame also includes forwardly disposed side members 27, the lower flanges 28 of which engage the 40 lower surfaces of the side frame members 15, and the vertical flanges 29 of which engage the inner surfaces of the side frame members 15. The flanges 28, 29 are secured to the wooden side frame members 15 by screws 30 passing through the flanges and threaded into the side 45 frame members.

Disposed between and integral with the rear member 21 and the side members 27 of the sub-frame 20 are diagonal members 31. These diagonal members 31 also have horizontal and vertical flanges 32, 33. Actually, the 50 forward members 27 of the sub-frame 20, the diagonal members 31 and the rear member 21 may be made integral merely by notching the horizontal flange of an angle iron, and by then bending the vertical flanges at the points of juncture between the rear member 21 and the diagonal members 31, and also between the diagonal members and the forward members 27.

An angle iron cross-piece member 34 is secured to and 55 between the diagonal members 31 between the rear member 21 and the forward members 27, as by use of welding material 35. This cross member 34 includes a horizontal flange 36 and a vertical flange 37, the horizontal flange being substantially coplanar with the other horizontal flanges of the sub-frame. The cross-piece is disposed at a particular location along the diagonal members 31, preferably being arranged substantially parallel to the rear member 21 of the sub-frame. The cross-piece is disposed at a particular location, to appropriately position the massage unit 19, which is secured by bolts 38, or the like, to the horizontal flange 36 of the cross-piece. The massage 60 unit 19 is adapted to impart a massaging or vibrating action to the sub-frame 20, which is transmitted from the sub-frame to the wooden frame members 14, 14a, 13, 15.

of the chair, and from the latter to the various padded regions of the chair.

The massage unit 19 specifically disclosed includes an electric motor 40 of any suitable type having its armature shaft 41 extending through and suitably secured to an eccentric 42, which is caused to rotate by the armature shaft. This eccentric 42 is secured within an inner race 43 carrying a set of ball bearing elements 44, which engage an outer race 45 to which a plurality of circumferentially spaced rubber inserts or segments 46 are secured, these rubber segments in turn being secured to the inner portion of a bearing support 47 integral with, or otherwise suitably secured to, an arm 48 extending transversely of the axis of the apparatus. The arm 48 is integral with a shoe plate 49 disposed outwardly of the motor and generally parallel to the axis of rotation of the armature shaft 41. The shoe plate extends lengthwise of the motor, its other end being integral with an inwardly extending arm 50, which is, in turn, integral with a cross member 51, to which the end of the motor frame remote from the eccentric is secured through the agency of a flexible coupling. The flexible coupling includes a plurality of bars 52, of fiber or other flexible material, secured to a frame flange 53 by screws 54, or the like, the flexible bars also being attached by screws 55 to the cross member 51.

If desired, a suitable cover member 56 may be placed over the bearing support 47, being secured thereto by screws 57, or the like. Similarly, another cover member 58 may be placed over the cross member 51 to house the flexible coupling 52, being suitably secured to the cross member 51 by screws, or the like. This last-mentioned cup-shaped cover member 58 may have an axial opening 59 in its end wall through which an electric line 60 leading from the motor 40 can pass. The other end of the line 60 is connected to a switch and rheostat 61 to which an electric cord or line 62 is connected. This line 62 has a plug at its terminus for insertion in a suitable electric outlet or socket (not shown). The switch and rheostat 61 may be suitably supported on the exterior portion of one of the side arm sections 12 for easy manipulation by a person seated within the chair.

The massage or vibratory unit 19 is secured to the horizontal flange 36 of the cross-piece 34 and substantially midway along its length, with the axis of rotation of the armature shaft disposed substantially parallel to the cross-piece 34 and to the rear member 21 of the sub-frame 20. Thus, the shoe plate 49 is secured to the horizontal flange of the cross-piece by the spaced bolts 38 to locate the unit in the relative position just described. As the motor 40 rotates, the eccentric 42 mounted thereon will produce a gyratory or vibratory action upon the arms 48, 50 and the shoe plate 49, which is transmitted to the cross-piece 34, and through the latter to the remainder of the sub-frame 20. From the rear 21 and forward portions 27 of the sub-frame, the vibratory action is transmitted to the wooden frame structure 13, 14, 14a, 15, 26, or other frame structure, of the chair. The massaging action, which is actually in the form of a circular motion, is imparted through the sponge rubber or other pliant, elastic padding of the seat 10 to the body of the person on the seat, as well as through the front 17 of the chair to the person's legs. It is also transmitted through the foam rubber padding to the arms of the person resting upon the arm portions 12 of the chair, and through the back 11 of the chair to the person's back, shoulder blades and neck.

The massage unit 19 is located in a particular position in the bottom frame structure 20, which, it is found, will effectively transmit the massaging action substantially uniformly throughout the entire chair structure. It is found that the spacing of the cross-piece 34 and the location of the massage unit 19 from the rear member 21 of the sub-frame and rear chair portion 14a, a distance which is approximately 30 percent of the distance between the rear

member 14a and the front frame 13 of the chair, an effective and substantially uniform massaging action is imparted to all parts of the chair. The substantial uniformity in the transmission of the massaging action throughout the chair is retained if the above percentage is varied by about 5 percent. Thus, if the distance of the cross-piece 34 in the massage unit from the rear member 14a is 25 percent to 35 percent of the distance from the rear member 14a to the front frame member 13 of the chair, an effective massaging action is transmitted throughout the chair, although if the above distance is the 30 percent value previously described, the transmission is most effective and efficient. Variations from the value of the 30 percent given above to a greater extent than 5 percent will reduce the effectiveness of the vibration transmission attached to the chair. As an example, if the vibration unit 19 is mounted on the frame too close to the rear member 14a, then the vibrations will be imparted predominantly to the back portion 11 of the chair and will be considerably reduced at the front portion 17 of the chair. Similarly, if the cross-piece 34 and massage unit 19 are disposed substantially forward of the chair, then the massaging action will predominate at the forward portion of the chair, and will not be transmitted effectively to the back portion 11 of the chair.

It is, accordingly, evident that the critical location of the cross-piece 34 and the massage unit 19 at the place indicated in the frame structure 13, 14, 14a, 15 produces effective transmission of the massage action throughout the chair. Moreover, the particular sub-frame 20 illustrated is economical to manufacture, providing a simple and effective manner of properly mounting and locating the massage unit 19 on the chair structure.

The padded back of the chair is specifically designed to impart effective massaging action to the different regions of a person's back, shoulders and neck. In effect, the padded back part of the chair is divided into three sections 11a, 11b, 11c. Thus, a lower section 11a that is convex in a forward direction is adapted to engage the lower portion of the person's back seated in the chair. The intermediate convex section 11b is adapted to engage the upper portion of the back, and the uppermost convex section 11c is adapted to engage the person's neck, and also the person's shoulders. It is found that a more effective massaging action is imparted to the rear of the person's body, and extending from the back to the neck, if the curvature of the upper section 11c is made relatively abrupt, the curvature being much sharper and pronounced than if the curvature were made to lie upon a circle. The curvature at the bottom portion 11a of the chair back also does not lie on a circle, the extent of its curvature being much flatter than the curvature of the upper portion 11c of the chair. The intermediate portion 11b of the chair back has a relatively flat curvature.

With the particular back curvatures described and shown, the lower portion 11a of the chair back is adapted to fit effectively within the small of a person's back, while the intermediate portion 11b is shaped to effectively fit the major length of the back, running up to the person's neck. The uppermost portion 11c of the chair is designed to appropriately fit against the person's neck, with the lower surface 11d of the upper portion 11c being adapted to engage the person's shoulders. The contour of the chair back 11 provides a relatively snug engagement between the lower section 11a with the lower portion of the person's back, the intermediate section 11b with the upper portion of the person's back, and the upper section 11c with the person's neck and shoulder area.

The inventor claims:

1. In chair apparatus: a chair base frame including front, rear and side members secured together; a seat and back supported by said frame, said back extending upwardly from said frame with its lower portion adjacent the rear of said seat, said seat and back each in-

cluding a layer of pliant, elastic material; a bottom frame secured to the rear and side members of said chair base frame; rotatable vibration producing means secured to said bottom frame with its rotational axis substantially parallel to said front and rear members; said rotational axis being spaced from said rear member from 25 percent to 35 percent of the distance between said front and rear members.

2. In chair apparatus: a chair base frame including front, rear and side members secured together; a seat and back supported by said frame, said back extending upwardly from said frame with its lower portion adjacent the rear of said seat, said seat and back each including a layer of pliant, elastic material; a bottom frame secured to the rear and side members of said chair base frame; rotatable vibration producing means secured to said bottom frame with its rotational axis substantially parallel to said front and rear members; said rotational axis being spaced from said rear member about 30 percent of the distance between said front and rear members.

3. In chair apparatus: a chair frame including front, rear and side members secured together; a seat and back supported by said frame, said seat and back each including a layer of pliant, elastic material; a bottom frame including a rear section secured to said rear member, forward sections secured to said side members, diagonal sections extending between and secured to said rear and forward sections, and a cross-section substantially parallel to said rear section and extending between and secured to said diagonal sections; and rotatable vibration producing means secured to said cross-section with its rotational axis substantially parallel to said rear section.

4. In chair apparatus: a chair frame including front, rear and side members secured together; a seat and back supported by said frame, said seat and back each including a layer of pliant, elastic material; a bottom frame including a rear section secured to said rear member, forward sections secured to said side members, diagonal sections extending between and secured to said rear and forward sections, and a cross-section substantially parallel to said rear section and extending between and secured to said diagonal sections; and rotatable vibration producing means secured to said cross-section with its rotational axis substantially parallel to said rear section; said rotational axis being spaced from said rear member from 25 percent to 35 percent of the distance between said front and rear members.

5. In chair apparatus: a chair base frame including front, rear and side members secured together, all of said members being substantially horizontal; a seat and back supported by said frame, said back extending upwardly from said frame with its lower portion adjacent the rear of said seat, said seat and back each including a layer of pliant, elastic material against which a person's body can rest; said back comprising a lower forwardly facing convex portion adapted to engage the lower region of a person's back, an intermediate forwardly facing convex portion adapted to engage the upper region of a person's back, and an upper forwardly facing convex portion adapted to engage a person's neck; a bottom frame secured to said chair base frame; rotatable vibration producing means secured to said bottom frame with its rotational axis substantially parallel to said front and rear members; said rotational axis being spaced from said rear member from 25 percent to 35 percent of the distance between said front and rear members.

6. In chair apparatus: a chair frame including front, rear and side members secured together; a seat and back supported by said frame, said seat and back each including a layer of pliant, elastic material against which a person's body can rest; said back comprising a lower forwardly facing convex portion adapted to engage the lower region of a person's back, an intermediate forwardly facing convex portion adapted to engage the

upper region of a person's back, and an upper forwardly facing convex portion adapted to engage a person's neck; the curvature of said lower portion being substantially more pronounced than said intermediate portion, and the curvature of the upper portion being substantially more pronounced than said lower portion; a bottom frame secured to said chair frame; rotatable vibration producing means secured to said bottom frame with its rotational axis substantially parallel to said front and rear members; said rotational axis being spaced from said rear member from 25 percent to 35 percent of the distance between said front and rear members.

7. In chair apparatus: a chair frame including front, rear and side members secured together; a seat and back supported by said frame, said seat and back each including a layer of pliant, elastic material against which a person's body can rest; said back comprising a lower forwardly facing convex portion adapted to engage the lower region of the person's back, an intermediate forwardly facing convex portion adapted to engage the upper region of a person's back, and an upper forwardly facing convex portion adapted to engage the person's neck; a bottom frame including a rear section secured to said rear member, forward sections secured to said side members, diagonal sections extending between and secured to said rear and forward sections, and a cross-section substantially parallel to said rear section and extending between and secured to said diagonal sections; and rotatable vibration producing means secured to said cross-section with its rotational axis substantially parallel to said rear section.

8. In chair apparatus: a chair frame including front, rear and side members secured together; a seat and back supported by said frame, said seat and back each including a layer of pliant, elastic material against which a person's body can rest; said back comprising a lower forwardly facing convex portion adapted to engage the lower region of the person's back, an intermediate forwardly facing convex portion adapted to engage the upper region of a person's back, and an upper forwardly facing convex portion adapted to engage the person's neck, the curvature of said lower portion being substantially more pronounced than said intermediate portion, and the curvature of said upper portion being substantially more pronounced than said lower portion; a bottom frame including a rear section secured to said rear member, forward sections secured to said side members, diagonal sections extending between and secured to said rear and forward sections, and a cross-section substantially parallel to said rear section and extending between and secured to said diagonal sections; and rotatable vibration producing means secured to said cross-section with its rotational axis substantially parallel to said rear section.

9. In chair apparatus: a generally rectangular chair base frame including front, rear and side members secured together; feet adapted to engage a floor secured to the four corners of said frame; a seat and back supported by said frame, said back extending upwardly from said frame with its lower portion adjacent the rear of said seat, said seat and back each including a layer of pliant, elastic material; a bottom frame secured to the rear and side members of said chair base frame; rotatable vibration producing means secured to said bottom frame with its rotational axis substantially horizontal and parallel to said front and rear members; said rotational axis being spaced from said rear member from 25 percent to 35 percent of the distance between said front and rear members.

10. In chair apparatus: a generally rectangular chair base frame including front, rear and side members secured together; feet adapted to engage a floor secured to the four corners of said frame; a seat and back supported by said frame, said back extending upwardly from said frame with its lower portion adjacent the rear of

said seat, said seat and back each including a layer of pliant, elastic material; a bottom frame secured to the rear and side members of said chair base frame; rotational vibration producing means secured to said bottom frame with its rotational axis substantially horizontal and parallel to said front and rear members; said rotational axis being spaced from said rear member about 30 percent of the distance between said front and rear members.

11. In chair apparatus: a generally rectangular chair base frame including front, rear and side members secured together; feet adapted to engage a floor secured to the four corners of said frame; a seat and back supported by said frame, said back extending upwardly from said frame with its lower portion adjacent the rear of said seat, said seat and back each including a layer of pliant, elastic material against which a person's body can rest; said back comprising a lower forwardly facing convex portion adapted to engage the lower region of the

person's back, an intermediate forwardly facing convex portion adapted to engage the upper region of the person's back, and an upper forwardly facing convex portion adapted to engage the person's neck; a bottom frame secured to said chair base frame; rotational vibration producing means secured to said bottom frame with its rotational axis substantially parallel to said front and rear members; said rotational axis being spaced from said rear member from 25 percent to 35 percent of the distance between said front and rear members.
